(57) **CLAIM**

I claim the ornamental design for an accessory retainer and housing of a folding multipurpose hand tool, as shown and described.

DESCRIPTION

FIG. 1 is a perspective view of an accessory retainer and housing of a folding multipurpose hand tool according to my new design, shown in the environment of a folding multipurpose hand tool with pliers in an open position;

FIG. 2 is a right side elevation view thereof;

FIG. 3 is a front elevation view thereof;

FIG. 4 is an enlarged partial view of FIG. 3

FIG. 5 is a top plan view thereof;

FIG. 6 is a rear elevation view thereof;

FIG. 7 is a left side elevation view thereof;

FIG. 8 is a bottom plan view thereof;

FIG. 9 is a perspective view of accessory retainer and housing of a folding multipurpose hand tool, shown in the environment of the folding multipurpose hand tool in a closed position;

FIG. 10 is an enlarged partial view of FIG. 9;

FIG. 11 is a rear elevation view of FIG. 9;

FIG. 12 is a right side elevation view of FIG. 9;

FIG. 13 is a front elevation view of FIG. 9;

FIG. 14 is a top plan view of FIG. 9;

FIG. 15 is a bottom plan view of FIG. 9;

FIG. 16 is a left side elevation view of FIG. 9;

FIG. 17 is a cross-sectional view taken from FIG. 16;

FIG. 18 is an enlarged partial view of FIG. 16; and,

FIG. 19 is a front elevation view thereof, shown in the environment of the folding multipurpose hand tool with a knife blade in an operable position.

The broken lines shown herein are for illustrative purposes only and form no part of the claimed design.
